(57) **CLAIM**

The ornamental design for a wearable device module for heating and cooling, as shown and described.

DESCRIPTION

FIG. 1 is a bottom perspective view of a wearable device module for heating and cooling;

FIG. 2 is a front elevation view of the wearable device module for heating and cooling of FIG. 1;

FIG. 3 is a rear elevation view of the wearable device module for heating and cooling of FIG. 1;

FIG. 4 is a top view of the wearable device module for heating and cooling of FIG. 1;

FIG. 5 is a bottom view of the wearable device module for heating and cooling of FIG. 1;

FIG. 6 is a left side elevation view of the wearable device module for heating and cooling of FIG. 1; the right side elevation being a mirror image thereof; and,

FIG. 7 is a cross sectional view of the wearable device module for heating and cooling for heating and cooling of FIG. 1.

The broken lines illustrate environmental structure and form no part of the claimed design.
